Primary Examiner — Ricky Pham*(74) Attorney, Agent, or Firm* — Belles Katz LLCCLAIM

The ornamental design for a cooking appliance, as shown and described.

DESCRIPTION

FIG. 1 is a perspective view of a cooking appliance according to our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dashed broken lines illustrate portions of the cooking appliance that form no part of the claimed design. The dot-dash broken lines illustrate the bounds of the claim and form no part of the claimed design.
